UNITED STATES PATENT OFFICE

BERNHARD HASENSTAB, OF BUFFALO, NEW YORK, ASSIGNOR TO MARKEL ELECTRIC PRODUCTS, INC., OF BUFFALO, NEW YORK, A CORPORATION OF NEW YORK

DESIGN FOR A BODY ELEMENT FOR AN ELECTRIC-LIGHT FIXTURE

Application filed May 27, 1930. Serial No. 35,785. Term of patent 3½ years.

To all whom it may concern:

Be it known that I, BERNHARD HASENSTAB, a citizen of the United States, residing at Buffalo, in the county of Erie and State of New York, have invented a new, original, and ornamental Design for a Body Element for an Electric-Light Fixture, of which the following is a specification, reference being had to the accompanying drawing, forming part thereof.

In said drawing:

Figure 1 is an elevation of a body element for an electric light fixture embodying my new design.

Figure 2 is a plan view of the same; in this figure one radial arm and a sector of the central hub are shown in full lines, it being understood that the remainder of the figure shown in dot and dash outline is to be similarly ornamented as the part fully illustrated.

I claim:

The ornamental design for a body element for an electric light fixture, substantially as shown and described.

BERNHARD HASENSTAB.
